NECKERCHIEF SLIDE

Harold A. Nagel, Hickman Mills, Mo.

Application December 23, 1954, Serial No. 33,662

Term of patent 14 years

(Cl. D17—10)

Fig. 1.

Fig. 2.

Fig. 3.

Fig. 4.

Fig. 1 is a front elevational view of a neckerchief slide, showing my new design;

Fig. 2 is a side elevational view thereof;

Fig. 3 is a rear elevational view thereof; and

Fig. 4 is a top plan view of the neckerchief slide.

I claim:

The ornamental design for a neckerchief slide, as shown.
